RUSLING WOOD, OF EAST ORANGE, NEW JERSEY, ASSIGNOR TO RUSLING WOOD INC., OF NEW YORK, N. Y., A CORPORATION OF NEW YORK

NECKBAND FOR BOTTLES

Application filed August 23, 1930. Serial No. 477,410.

This invention relates to neck bands for bottles and particularly to an improved band for a milk bottle, the object being to provide a construction which will snugly fit the neck and upper part of the bottle and which may be readily applied or removed at any time.

Another object of the invention is to provide a neck band for milk bottles wherein the same is made from a single piece of paper or other sheet material, the ends being connected by a latch which is swingable, whereby the band may be cone shaped and yet the small end enlarged or contracted according to circumstances as the band is placed over the top of the bottle and forced downwardly to the lower part of the neck.

A further object of the invention is to provide a neck band for milk bottles formed of an arc-shaped blank with the ends connected by an articulated connection, and with means presenting lines for classified information.

In the accompanying drawings—

Figure 1 is a plan view of the blank of a neck band disclosing an embodiment of the invention;

Figure 2 is a side view of the blank placed on top of a milk bottle;

Figure 3 is a top plan view of the structure shown in Figure 2;

Figure 4 is a view similar to Figure 2 but with the parts swung so as to enlarge the small end of the circular band whereby it may pass over the top of the bottle;

Figure 5 is a top plan view of the structure shown in Figure 4;

Figure 6 is a side view of the complete milk bottle with the band embodying the invention shown applied thereto.

Figure 7 is a fragmentary view similar to the left hand end of Figure 1 but illustrating another form of the invention.

Referring to the accompanying drawings by numerals, 1 indicates the body of the band which is arc shaped and is provided with an interlocking tab 2 at one end having undercuts or notches 3 and 4, said tab when used being adapted to be inserted through the notch 5 with the sections 6 and 7 extending beyond the respective points 8 and 9. It will

be noted that the opening 5 is substantially triangular so that there will be allowed articulation of the respective parts such articulation or movement being equal to the length of the line 10.

When the tab 2 is interlocked with the opposite end of the sheet 1 it forms a truncated cone as shown in Figure 2 and when placed on top of a bottle 11 will rest on the bead 12 thereof as the smaller opening of the device is of less diameter than the average bead 12 on a milk bottle. However, by reason of the articulation of the latch or connecting tab 2 with its associated parts at the opposite end of the body, the body may be distorted or twisted so that the parts will be swung to the position shown in Figure 4 so that the small end will open substantially to the same extent as the length of line 10, whereby the band may readily slip over the bead 12 of bottle 11. A soon as it passes the bead 12 it will quickly and automatically assume the truncated cone position as shown in Fig. 2 by reason of the resiliency of the paper. However, the band is forced downwardly by gravity and usually by the hand of the workman until it fits snugly at the juncture of the neck of the bottle, as shown in Figure 6. When in this position the shoulders or parts 6 and 7 will be pressing against the wall 13.

The band is adapted to carry any desired advertisement and in addition is provided with a record or information section 14. This section is supplied with a number of lines 15 and preferably opposite certain of these lines will be found the words Name, Address and Order, so that when a bottle of milk is delivered the housewife or other person may remove the band and write an order on the lines 15, thereafter replacing the band on an empty bottle so that when the milk man collects the bottles he will find the order and act accordingly.

Preferably the band is made from a fair grade of paper but, preferably, only sufficiently strong to be used once. Consequently it can be made very cheaply so that the person using the device for advertising purposes may secure the desired advertising at a minimum cost, and in addition the company or

firm delivering the milk will be provided with a convenient memorandum sheet for receiving orders from the housewife for extra supplies. Heretofore it has been customary to write an order on a piece of paper and place the same in the open neck of the milk bottle. Sometimes these loose pieces of paper become lost and consequently the order is not filled. By the use of the neck band an order may be properly placed thereon and the band then replaced on the bottle where it will remain until positively removed.

In Figure 7 another or modified form of the invention is shown, the same being identical with that shown in Figure 1 except that the notch or opening consists of an L-shaped slit 16. By reason of this structure the material 17 is left in place but the lines or walls 13 and 10 are present whereby the tab 2 may properly interlock in the same manner as shown in Figures 1 to 6, inclusive. This structure is desirable as the die will cut the slit 16 readily and at high speed while the opening or notch 5 requires more care in operating the die, although when constructed it functions identically with the L-shaped slit or notch 16.

What I claim is:—

1. A neck band for milk bottles comprising an arc-shaped body having a substantially triangular shaped notch at one end and a tab at the opposite end, said tab having overhanging shoulders, said tab being adapted to be inserted through said notch with the shoulder portions extending beyond the notch to produce a latching operation, said tab being adapted to swing by reason of the shape of said notch so that the smaller end of the band may have its diameter increased when desired.

2. A truncated cone band for milk bottles formed from an arc shaped blank provided with a tab at one end and a notch at the opposite end, said notch being larger at one end than the other whereby there may be a swinging motion between the respective ends so as to permit an enlargement of the diameter on the small end of the cone.

3. In a neck band for milk bottles, a blank comprising an arc shaped body formed of the same width at all points, said body at one end having an opening, having two of its walls presenting an L-shaped outline, said opening being arranged with its base substantially parallel with the top and bottom edges of the blank and its altitude substantially parallel with one end of the blank, and a tab extending from the opposite end of said blank to said opening, said tab having a restricted portion or neck and overhanging shoulders on each side of said neck.

4. In a neck band for milk bottles, a blank comprising an arc-shaped body, said body at one end having an opening positioned with one wall thereof substantially parallel with

the end of the blank and a second wall substantially parallel with the top and bottom edges of the blank, and a tab extending from the opposite end of said blank opposite to said opening, said tab having a restricted portion at the neck and overhanging shoulders at each side of the neck.
